UNITED STATES PATENT OFFICE.

HENRY IVES, OF PUEBLO, COLORADO, ASSIGNOR OF ONE-HALF TO SAMUEL F. CRAWFORD AND WILLIAM F. DRAKE, OF SAME PLACE.

DESIGN FOR A MATTRESS.

SPECIFICATION forming part of Design No. 29,001, dated July 5, 1898.

Application filed June 28, 1897. Serial No. 642,755. Term of patent 14 years.

To all whom it may concern:

Be it known that I, HENRY IVES, a citizen of the United States, residing at Pueblo, in the county of Pueblo and State of Colorado, 5 have invented a new and original Design for a Mattress, of which the following is a specification.

This invention relates to a new and original design for a mattress; and it has for its object 10 to provide a design of this character that shall be both useful and ornamental.

The leading feature of the design resides in a rectangular oblong mattress-body provided with duplicate upper and lower surfaces having a series of parallel closely-arranged transverse rounded convex portions extending continuously from side to side of the body and meeting at their adjacent edges in angular depressions or creases alternating with said 15 rounded convex portions, said body also having on the surface thereof parallel rows of alternate light and dark stripes running longitudinally thereof and crossing said rounded convex portions at right angles to the length 20 of the latter.

A minor feature of the design resides in the body, having at the narrow side edges thereof a longitudinal series of approximately rectangular convex figures and reentrant creases 25 alternating therewith.

In the drawings, Figure 1 is a perspective view of a mattress-body embodying the herein-described design. Fig. 2 is a longitudinal sectional view thereof.

Referring to the accompanying drawings, 35 the numeral 1 designates an oblong rectangular mattress-body, whose upper and lower duplicate surfaces are provided with a series of parallel closely-arranged rounded convex portions 2. These convex portions 2 extend 40 continuously from side to side of the body and have their edges meet to form V-shaped or angular depressions or creases 3, which alternate with the convex portions 2, and also extend from side to side of the body. On the 45 surfaces thereof the said body is also provided with parallel rows of alternate light and dark stripes, running longitudinally of the body and crossing said rounded convex portions at right angles to the length of the latter. 50

At its narrow side edges the mattress-body 1 is provided with a longitudinal series of approximately rectangular convex figures 4 and reentrant vertically-disposed creases 5 alternating therewith. 55

What is claimed as new is—

The design for a mattress herein shown and described.

In testimony that I claim the foregoing as my own I have hereto affixed my signature in 60 the presence of two witnesses.

HENRY IVES.
